UNITED STATES PATENT OFFICE.

WILLIAM EVENSEN, OF CHICAGO, ILLINOIS, ASSIGNOR TO THE GOSS PRINTING PRESS COMPANY, OF CHICAGO, ILLINOIS, A CORPORATION OF ILLINOIS.

PAWL-AND-RATCHET DRIVING MECHANISM.

1,163,815.

Specification of Letters Patent. Patented Dec. 14, 1915.

Application filed March 12, 1915. Serial No. 13,871.

To all whom it may concern:

Be it known that I, WILLIAM EVENSEN, a citizen of the United States, residing at Chicago, in the county of Cook and State 5 of Illinois, have invented certain new and useful Improvements in Pawl-and-Ratchet Driving Mechanism, of which the following is a specification, reference being had to the accompanying drawings.

10 My invention relates to pawl and ratchet driving mechanism especially designed for use in connection with the inking mechanism of a printing press, in connection with which it is shown in my drawings.

15 It is the object of my invention to provide an improved silent ratchet mechanism applicable to the requirements of such a device in connection with inking mechanisms, by reason of which the inking roll of an ink

20 fountain may be given a positive intermittent rotation and the driving pawl may be lifted clear of its coöperating ratchet when not in operative engagement therewith or may be readily lifted and automatically

25 held out of operative engagement whenever it is desired to stop the rotation of the inking roll. The means by which I have accomplished this object are illustrated in the accompanying drawings and are hereinafter 30 specifically described.

That which I believe to be new and desire to cover by this application is set forth in the claims.

In the drawings: Figure 1 is a side view 35 of a portion of a press illustrating my improved silent ratchet mechanism in connection with an ink fountain; Fig. 2 is a central vertical section through the parts shown in Fig. 1, being taken substantially on line 2—2 40 of said figure; and Fig. 3 is an enlarged detail showing the means for holding the pawl out of operative position, being substantially a section taken on line 3—3 of Fig. 1, but with the pawl lifted and held in its in- 45 operative position.

Referring to the several figures of the drawings in which corresponding parts are indicated by the same reference characters, 50 indicates the framework of a press having an inking roller 11 journaled therein within an ink trough 12 by means of a shaft 13. Revolubly mounted upon the outer end of the shaft 13 is a sleeve 14 having formed

with it a segmental rack 15 with which meshes a rack-bar 16 which is adapted to be 55 reciprocated by any suitable source of power for driving the sleeve 14 alternately in opposite directions. Rising from the sleeve 14 is an arm 17 by which the said sleeve may be rotated manually, as desired. An arc-shaped plate 18 is attached to the framework 60 10 in any suitable manner, serving in connection with an arc-shaped plate 19 mounted upon the arm 17 to guide the arm 17 as it is actuated through the medium of 65 the sleeve 14 and the rack-bar 16, as herein-after described. The arc-shaped plate 18 is provided with a longitudinally-extending slot 20 in which a block 21 is adapted to be 70 adjustably secured for limiting the counter-clockwise movement of the arm 17 in Fig. 1. A roller 22 is revolubly mounted adjacent to the rack-bar 16 for holding the said rack-bar in proper engagement with the segmental rack 15. Inasmuch as the parts so 75 far described are well-known in the art, it is not believed to be necessary to further describe them herein.

A ratchet-wheel 23 is fixed upon the shaft 13 adjacent to the sleeve 14, upon a laterally-extending hub 24 of which is revolubly mounted a split friction-ring 25, the said friction-ring being held against withdrawal from the said hub 24 by means of a washer 26 secured in any suitable manner to the end 85 of the shaft 13. Rising from the friction sleeve 25 is an arm 27 having pivotally connected to its upper end a link 28 which in turn is pivotally connected to a dog or pawl 29 which is pivotally mounted by means of a 90 bolt 30 upon the arm 17 in position to engage the teeth of the ratchet-wheel 23.

As will be readily understood from a study of Fig. 1, when the rack-bar 16 is raised, serving to turn the sleeve 14 and the 95 arm 17 in clockwise direction in Fig. 1, the pawl 29 is moved in the same direction with the said arm 17. The friction-ring 25, however, grips the hub 24 of the ratchet wheel 23 so as to resist a like movement of the said 100 ring 25, thereby exerting a backward and downward pull upon the pawl 29 through the medium of the link 28. The operative end of the pawl 29 is consequently moved downward into operative engagement with 105 the ratchet wheel, causing during the con-

tinued clockwise movement of the arm 17 in said Fig. 1 a corresponding clockwise movement of the ratchet-wheel 23, the shaft 13 and the inking roller 11. Upon the reversal 5 of the direction of movement of the rack-bar 16, the sleeve 14 and the arm 17 will likewise have their direction of movement changed, serving to carry the pawl 29 in counterclockwise direction in said Fig. 1. The friction-ring 25 again resists a like movement of itself relative to the hub 24, whereby the operative end of the pawl 29 receives an upward impulse through the medium of the link 28, serving to swing the pawl 29 out of 15 contact with the teeth of the ratchet-wheel, the frictional engagement of the split sleeve 25 upon the hub 24 being insufficient to cause a rotation of the ratchet 23 and its connected parts in counterclockwise direction in said 20 Fig. 1 with the arm 17.

Whenever it is desired to operate the ink fountain manually, this can be accomplished through the medium of the arm 17, the operation being just the same as that above 25 described, except in the matter of the force by which the rotation of the sleeve 14 is produced. It will be understood that in the construction shown, the rack-bar 16 would be reciprocated upon the manual actuation 30 of the arm 17, thus making it necessary that a proper yielding connection be provided between the rack-bar 16 and its normal actuating means. Inasmuch as connections of this type are in common use and form no 35 part of my present invention, it is believed to be unnecessary to illustrate them herein.

Whenever it is desired to stop the operation of the inking fountain without stopping the operation of the rack-bar 16, this may be 40 accomplished by raising the dog or pawl 29 out of contact with the ratchet wheel 23 until the recess 31 formed in the side face of the dog 29 is brought into engagement with a pin 32 which is pressed outward for such 45 engagement at the proper moment by a spring 33 mounted in the socket 34 in the arm 17 within which the pin 32 is slidably mounted. The spring 33 is designed to be of such strength that the dog 29 will be held 50 in its turned inoperative position, as just described, against the pull of the friction sleeve 25 through the medium of the link 28, as the sleeve is actuated.

What I claim as my invention and desire 55 to secure by Letters Patent, is—

1. In a pawl and ratchet driving mechanism, the combination of an oscillatory driving member, a member to be driven revolubly mounted relative to the said driving 60 member, a pawl carried by one of said members, a ratchet-wheel fixed against rotation relative to the other of said members in position to be operatively engaged by said pawl, a friction-ring revolubly mounted on 65 said ratchet-wheel, and connections between

said friction-ring and said pawl serving to draw said pawl into operative engagement with the ratchet-wheel upon the rotation of said driving member in one direction and to throw the said pawl out of contact with 70 said ratchet-wheel upon the rotation of said driving member in the opposite direction.

2. In a pawl and ratchet driving mechanism, the combination of an oscillatory driving member, a member to be driven 75 revolubly mounted relative to said driving member, a pawl pivotally mounted on said driving member, a ratchet-wheel fixed upon the other of said members in position to be operatively engaged by said pawl, a friction-ring revolubly mounted on said ratchet-wheel, and connections between said friction-ring and said pawl serving to draw said pawl into operative engagement with the ratchet-wheel upon the rotation of said 80 driving member in one direction and to throw the said pawl out of contact with said ratchet-wheel upon the rotation of said driving member in the opposite direction.

3. In a pawl and ratchet driving mechanism, the combination of a shaft, a sleeve revolubly mounted thereon, means for rocking one of said members alternately in opposite directions, a pawl carried by one of said members, a ratchet-wheel fixed against 95 rotation relative to the other of said members in position to be operatively engaged by said pawl, a friction-ring revolubly mounted on said ratchet-wheel, and connections between said friction-ring and said pawl serving to draw said pawl into operative engagement with the ratchet-wheel upon the rotation of said driving member in one direction and to throw the said pawl out of contact with said ratchet-wheel upon the rotation of said 100 driving member in the opposite direction.

4. In a pawl and ratchet driving mechanism, the combination of a shaft, a sleeve revolubly mounted thereon, means for rocking said sleeve about said shaft, a pawl pivotally mounted on said sleeve, a ratchet-wheel fixed on said shaft in position to be operatively engaged by said pawl, a friction-ring revolubly mounted on said ratchet-wheel, and connections between said friction-ring and said pawl serving to draw said pawl into operative engagement with the ratchet-wheel upon the rotation of said 110 driving member in one direction and to throw the said pawl out of contact with said ratchet-wheel upon the rotation of said driving member in the opposite direction.

5. In a pawl and ratchet driving mechanism, the combination of an oscillatory 115 driving member, a member to be driven revolubly mounted relative to the said driving member, a pawl carried by one of said members, a ratchet-wheel fixed against rotation relative to the other of said members 120

125

in position to be operatively engaged by said pawl, a friction-ring revolubly mounted on a hub extending from one side of said ratchet-wheel, and connections between said friction-ring and said pawl serving to draw said pawl into operative engagement with the ratchet-wheel upon the rotation of said driving member in one direction and to throw the said pawl out of contact with said ratchet-wheel upon the rotation of said driving member in the opposite direction.

6. In a pawl and ratchet driving mechanism, the combination of an oscillatory driving member, a member to be driven revolvably mounted relative to the said driving member, a pawl carried by one of said members, a ratchet-wheel fixed against rotation relative to the other of said members in position to be operatively engaged by said pawl, a split ring revolvably mounted on a hub extending from one side of said ratchet-wheel and frictionally engaging the same, and connections between said friction-ring and said pawl serving to draw said pawl into operative engagement with the ratchet-wheel upon the rotation of said driving member in one direction and to throw the said pawl out of contact with said ratchet-wheel upon the rotation of said driving member in the opposite direction.

7. In a pawl and ratchet mechanism, the combination of a shaft, a sleeve revolubly mounted thereon, means for rocking said sleeve about said shaft, an arm fixed on said sleeve, 35 a pawl pivotally mounted on said arm, a ratchet-wheel fixed on said shaft in position to be operatively engaged by said pawl, a friction-ring revolubly mounted on said ratchet-wheel, and a link pivotally connecting said friction ring with said pawl serving to draw said pawl into operative engagement with the ratchet-wheel upon the rotation of said sleeve in one direction and to throw the said pawl out of contact with 40 said ratchet-wheel upon the rotation of said sleeve in the opposite direction.

8. In a pawl and ratchet driving mechanism, the combination of an oscillatory driving member, a member to be driven revolubly mounted relative to the said driving member, a pawl carried by one of said members, a ratchet-wheel fixed against rotation relative to the other of said members in position to be operatively engaged by said pawl, a friction-ring revolubly mounted on said ratchet-wheel, connections between said friction-ring and said pawl serving to draw said pawl into operative engagement with the ratchet-wheel upon the rotation of said driving member in one direction and to throw the said pawl out of contact with said ratchet-wheel upon the rotation of said driving member in the opposite direction, and means adapted automatically to hold said pawl turned out of operative engagement

with the ratchet-wheel when the pawl has been turned to a predetermined position.

9. In a pawl and ratchet driving mechanism, the combination of an oscillatory driving member, a member to be driven revolubly mounted relative to the said driving member, a pawl carried by one of said members, a ratchet-wheel fixed against rotation relative to the other of said members in position to be operatively engaged by said pawl, a friction-ring revolubly mounted on said ratchet-wheel, connections between said friction-ring and said pawl serving to draw said pawl into operative engagement with the ratchet-wheel upon the rotation of said driving member in one direction and to throw the said pawl out of contact with said ratchet-wheel upon the rotation of said driving member in the opposite direction, and spring-actuated means adapted to hold said pawl turned out of operative engagement with the ratchet-wheel when the pawl has been turned to a predetermined position. 70 75 80 85

10. In a pawl and ratchet driving mechanism, the combination of an oscillatory driving member, a member to be driven revolubly mounted relative to the said driving member, a pawl carried by one of said members, a ratchet-wheel fixed against rotation relative to the other of said members in position to be operatively engaged by said pawl, a friction-ring revolubly mounted on said ratchet-wheel, connections between said friction-ring and said pawl serving to draw said pawl into operative engagement with the ratchet-wheel upon the rotation of said driving member in one direction and to throw the said pawl out of contact with said ratchet-wheel upon the rotation of said driving member in the opposite direction, and means adapted to lock the said pawl yieldingly in turned position relative to said driving means when turned to a predetermined position out of operative engagement with said ratchet-wheel. 110

11. In a pawl and ratchet driving mechanism, the combination of an oscillatory driving member, a member to be driven revolubly mounted relative to the said driving member, a pawl carried by one of said members, a ratchet-wheel fixed against rotation relative to the other of said members in position to be operatively engaged by said pawl, a friction-ring revolubly mounted on said ratchet-wheel, connections between said friction-ring and said pawl serving to draw said pawl into operative engagement with the ratchet-wheel upon the rotation of said driving member in one direction and to throw the said pawl out of contact with said ratchet-wheel upon the rotation of said driving member in the opposite direction, and spring-actuated means adapted to hold said pawl turned out of operative engagement with the ratchet-wheel when the pawl 115 120 125 130

has been turned to a predetermined position, said spring-actuated means comprising a pin slidably mounted in said driving member and adapted to bear against said pawl,
5 and a spring serving to force said pin into engagement with a suitable recess in said pawl for holding the pawl yieldingly against

turning relative to said driving means when the pawl is turned to bring the said recess into alignment with said pin.

WILLIAM EVENSEN.
